(57) **CLAIM**

The ornamental design for a motorcycle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a motorcycle showing my new design.

FIG. 2 is a rear perspective view thereof.

FIG. 3 is a right side view thereof.

FIG. 4 is a left side view thereof.

FIG. 5 is a front right perspective view thereof.

FIG. 6 is a front left perspective view thereof.

FIG. 7 is a rear left perspective view thereof.

FIG. 8 is another rear left perspective view thereof.

FIG. 9 is a rear right perspective view thereof; and,

FIG. 10 is another front right perspective view thereof.

The broken lines around the removed logos and written matter and tires represent an internal boundary of the claimed design and form no part of the claimed design.

The bottom of the motorcycle forms no part of the claimed design.
